(57) CLAIM

The ornamental design for a bank box for holding money, as shown and described.

DESCRIPTION

FIG. 1 is a front, perspective view of a bank box for holding money showing my new design;

FIG. 2 is a left side view thereof;

FIG. 3 is a right side view thereof;

FIG. 4 is a front view thereof;

FIG. 5 is a rear view thereof;

FIG. 6 is a top plan view thereof;

FIG. 7 is a bottom plan view thereof;

FIG. 8 is another front, perspective view thereof, with the lid of the bank box being partially removed for ease of illustration; and,

FIG. 9 is another front, perspective view thereof, with the lid of the bank box fully removed for ease of illustration.
